UNITED STATES PATENT OFFICE.

MARCIK OSTROWIECKI, OF CHICAGO, ILLINOIS, ASSIGNEE OF ONE-HALF TO FRANK TARNAWSKI, OF CHICAGO, ILLINOIS.

SHIP-PROTECTOR.

1,261,848.

Specification of Letters Patent.

Patented Apr. 9, 1918.

Application filed August 20, 1917. Serial No. 187,235.

To all whom it may concern:

Be it known that I, MARCIK OSTROWIECKI, a citizen of Russia, residing at Chicago, in the county of Cook and State of Illinois, 5 have invented certain new and useful Improvements in Ship-Protectors, of which the following is a specification.

The primary object of the invention is the provision of a protector for ships designed 10 for preventing injury thereto by torpedoes and other missiles which are adapted to travel adjacent or beneath the surface of the water.

A further object of the device is the provision of a torpedo protector for ships whereby an oncoming torpedo is diverted 15 in its direction of travel to prevent any injury to the ship which is protected with the device.

20 In the drawings forming a part of this application like designating characters indicate corresponding parts throughout the several views.

Figure 1 is a side elevation of a ship provided with the present device.

Fig. 2 is a top plan view thereof.

Fig. 3 is a rear end elevation of the same.

Fig. 4 is a horizontal sectional view of a portion of the device illustrating a torpedo 30 in connection therewith, dotted lines being employed for illustrating the operation of the device.

Fig. 5 is an enlarged side elevation of a portion of the device broken away.

35 Fig. 6 is a top plan view of a boat provided with a modified form of the invention.

Fig. 7 is a side elevation of a forward portion thereof, and

40 Fig. 8 is a vertical transverse sectional view thereof.

Referring more in detail to the drawings, a ship 10 is illustrated comprising a hull 11, deck 12, cabin 13, a wireless device 14, and showing the protecting device positioned in 45 its protecting arrangement upon the hull 11.

Torpedo catching and course-diverting gates are disposed at a distance from the ship's hull at each side thereof. To support these gates I provide supporting brackets 50 each comprising an arc portion 20 which is attached to the hull, and an upper outwardly extending arm 21 and a lower outwardly extending arm 21', the arms extending parallel, one above the other. The outer ends

of the arms 21 of the brackets are connected 55 by a top rail 17, and the outer ends of the arms 21' are connected together by the bottom rail 18. The gates 16 are hung between said top rail 17 and the bottom rail 18, being supported normally with the lower rails of 60 the gates some distance above the lower rail 18. The gates each comprise a rectangular frame formed of a top rail, a bottom rail, and end rails, which frame carries a suitable net work 22. They are hung between the 65 rails at one end of the gate on pintles 23 and 24 respectively. The lower pindle 24 seats in a slot 25 provided therefor in the rail 18 while the upper pindle 23 is threaded into a socket 26 in the upper rail 17. The 70 sockets 26 are counter-bored as shown in Fig. 5 so as to leave but a single thread engagement with the pintles 23. The gates are held normally against displacement or 75 swinging movement by cords 27 tied around the rail 17 and upper rail of the gate frame, and also by similar cords tied around the lower rail of the gate frame and the rail 18.

In event of a torpedo as represented at 30 Fig. 4 striking one of the gates, the ties 27, 80 are broken by the strain of the torpedo against the gate, and the latter swings around upon its pintles 23-24, tending to divert the "oncoming" direction of the torpedo, the strain of the torpedo against the 85 gate serving at the same time to force pindle 24 out of the slot 25 in which it was normally maintained by the ties 27. Further swinging movement of the gate has unscrewed pindle 23 from its socket by which 90 time the gate is free of the rails 17 and 18 and has been moved around by the force of the torpedo to a course practically parallel with the course of the ship with the gate suspended thereon. Should the gate become 95 entangled with the arms 21-21', the torpedo will be held until its propelling power is exhausted, when its weight will cause it to sink harmlessly. The gate torn away by the torpedo may be readily replaced when 100 opportunity affords repairs.

In the form of the invention shown in Fig. 6, the boat 40 is arranged with mounting plates 41 which are H-shaped in cross section and adapted for the reception of perforated 105 panels 42 therebetween, the said plates being shiftably attached to the boat 40 by means of links 43.

The panels 42 are retained within the plates 41 by means of bolts or rivets 44. The links 43 have pivoted connections 45 for the plates 41 and are attached to the boat 40 by means of brackets 46 to which the links are pivoted. Stops 47 project from the boat 40 beneath the links 43 for limiting the downward movement of the links it being understood that the panels 42 will be arranged substantially upright in the water at opposite sides of the boat 40 when the links are so positioned.

Telescoping braces 47 connect the end plates 48 with the boat 40 the said stays having ball and socket connections 49 with the bolt and the plates 48. Arrangement is made for elevating the panels 42 out of the water when desired and for retaining the panels at any desired adjusted position, such arrangement being in the form of cables 50 attached as at 51 to the plates 41 and passing over pulley wheels 52 upon a frame 53 of the boat 40 and then arranged over winding drums 54 upon the boat. The cords 50 from opposite sides of the boat are so arranged upon the drum 54 that the panels 42 may be elevated simultaneously upon turning the said drums by means of the cranks 55 with which the same is provided. It will be seen that the panels 42 are normally arranged in the water at opposite sides of the boat 40 for protecting the same and any oncoming missile such as a torpedo will strike one of the panels 42 thereby preventing any damage to the boat 40. Upon any of the panels being injured the drums 54 may be turned for elevating the panels 42 and plates 41 to a point adjacent the deck of the boat as illustrated by dotted lines in Fig. 8 of the draw-

ings so that the injured plate may be repaired or replaced.

What I claim as new is:—

1. A protector for hulls comprising a frame longitudinally secured to the side of the hull and embodying upper and lower rails, the lower rail of said frame having shallow sockets therein and the upper rail provided with recessed perforations in vertical alinement with the said sockets, gates arranged between the said rails having pintles freely positioned within the said sockets and perforations and retaining loops between the said rails and gates adapted for normally maintaining the gates in longitudinal alinement.

2. In combination with the hull of a boat, a mounting frame positioned at a distance from the side of the hull and embodying upper and lower parallel rails, the said lower rail having a socket and the upper rail having a recessed perforation in vertical alinement with the said socket, a gate of net work formation, upper and lower pintles at one end of the gate freely arranged swingingly within the said socket and perforation and retaining loops between the said gate and rails adapted for normally maintaining the gate positioned therebetween.

3. A device of the class described, comprising in combination with a boat, a plurality of H-shaped plates, panels carried by the said plates, link connections between the plates and boat, telescoping stays pivotally connecting the end ones of said plates with the boat and elevating means for the plates and panels carried by the boat.

In testimony whereof I affix my signature.

MARCI OSTROWIECKI.

Copies of this patent may be obtained for five cents each, by addressing the "Commissioner of Patents, Washington, D. C."
